UNITED STATES PATENT OFFICE.

HENRY LEFEBER, OF PHILADELPHIA, PENNSYLVANIA, ASSIGNOR TO
ROBERT H. FARLEY, ISAAC KEELER, AND ALFRED P. PHIPPS, ALL
OF SAME PLACE.

QUILTING-MACHINE.

SPECIFICATION forming part of Letters Patent No. 437,439, dated September 30, 1890.

Application filed June 2, 1888. Serial No. 275,869. (No model.)

To all whom it may concern:

Be it known that I, HENRY LEFEBER, a citizen of the United States, and a resident of Philadelphia, Pennsylvania, have invented 5 certain Improvements in Quilting-Machines, of which the following is a specification.

The object of my invention is to construct a simple and efficient machine for forming plain or elaborate designs upon the fabric to 10 be quilted.

In the accompanying drawings, Figure 1 is a side elevation of my improved quilting-machine. Fig. 2 is a longitudinal section on the line 1 2, Fig. 3, drawn to an enlarged scale; 15 and Fig. 3 is a plan view showing the cam.

A is the base of the machine, and B is an arm carrying at its outer end a head C.

b is the needle-bar, which is driven through the medium of a cam in the head by the shaft 20 C', having preferably at its outer end a fly-wheel. This shaft is geared to a vertical shaft C² by bevel-gears c' c², and this shaft in turn is driven from the main shaft E through bevel-gears c³ c⁴. This main shaft is provided 25 with a pulley E' driven by a belt from any convenient power-driven shaft.

b' is the presser-bar, and b² is the presser-foot.

The needle mechanism and the presser-bar 30 mechanism are of the ordinary construction.

d is the take-up arm pivoted to the head C and governed by a cam mounted on the shaft C'.

a is a stud secured to or forming part of 35 the base-plate, and situated directly in line with the needle, and secured to this stud is a throat-plate a². The stud a is hollow, and in it is the rotary shuttle F, constructed in the following manner: The shuttle is mounted on

40 a revolving spindle f, driven through the medium of a crank-arm f' from one arm of a lever F', which is pivoted through the medium of a link f² to the base-plate of the machine. The other arm of the lever is yoked

45 and spans an eccentric C³, so that as the vertical shaft C² revolves the eccentric will vibrate the lever, and consequently the shuttle will be revolved. On the exterior of this shuttle F is a hook g of the peculiar form shown,

and through the center of this shuttle passes 50 a vertical spindle g' cut away at its upper end to allow for the formation of the loop of the needle-thread, and on this spindle is placed an ordinary spool of cotton, so that as the needle-bar is reciprocated and the needle 55 forms a loop the hook will enter the loop, carrying with it the spool or shuttle thread and pass the spool-thread through the loop, forming a lock-stitch.

I have shown one form of shuttle that can 60 be used in connection with my machine; but it will be understood that a shuttle of any ordinary construction may be used in its stead without departing from my invention.

On the base-plate A is an annular rim A', 55 forming a bearing for the gear-wheel G, by which the quilting-frame is revolved. This gear-wheel engages with a pinion H on an upright shaft H', having at its lower end a worm-wheel H², gearing with a worm H³ on the main 70 driving-shaft E. Carried by this gear-wheel is a quadrangular frame I, connected to the gear-wheel by spokes I'. The frame I has two longitudinal undercut ribs I² on two of its sides, and situated on the frame I is the 75 work-carrying frame K, having tapered ribs adapted to slide in the undercut portions of the frame I, so that it will be seen that the work-carrying frame can be moved toward 80 and from the center of the carrying-frame I as said carrying-frame is rotated.

Mounted in bearings j on the frame I is a cam J, having a groove j' of any irregular shape in its face. In this groove j' rests a pin m, having a friction-roller m'. This pin is 85 fastened to the under side of the work-carrying frame K.

On the shaft J' of the cam J is mounted a gear-wheel J², which meshes with an annular rack L on the base of the machine, so that as 90 the carrying-frame I revolves the cam will not only rotate around the axis of the gear-wheel G, but also around its own axis.

The operation of the machine is as follows: 95 The cloth is clamped or otherwise suitably secured to the work-carrying frame K. The machine is then set in motion by any suitable clutching or belt-shifting devices, and as the

needle reciprocates the frame I, carrying the cam J and the frame K, will revolve through the medium of the gear-wheel G and the gearing above described. As the frames revolve, 5 the pin m, carried by the work-frame K, is moved toward or from the center of rotation of the frame I, as the groove j' in the cam J dictates.

The cam can be readily removed and another 10 cam of a different character inserted to form different designs, when required.

When large pieces of fabric are to be quilted, one portion is quilted at a time and then moved and another portion clamped in position and quilted, and so on, until the quilting 15 is completed.

I claim as my invention—

1. The combination, in a quilting-machine, 20 of the sewing mechanism, the carrying-frame, and mechanism, substantially as described, for rotating said frame, with a work-frame guided on said carrying-frame, a cam mounted on the carrying-frame, a projection on the

work-frame meshing with the cam, and devices, substantially as specified, for operating 25 said cam.

2. The combination, in a quilting-machine, of the sewing mechanism, the carrying-frame, and mechanism for rotating said frame, with a work-frame guided on said carrying-frame, 30 a cam mounted on the carrying-frame, a pin on the work-frame engaging with said cam, a gear-wheel on the shaft of the cam, and an annular rack on the base of the machine engaging with the gear-wheel, so that on the rotation of the carrying-frame the work will be moved toward and from the center of rotation of the carrying-frame, substantially as set forth.

In testimony whereof I have signed my 40 name to this specification in the presence of two subscribing witnesses.

HENRY LEFEBER.
